UNITED STATES PATENT OFFICE.

JOHN L. LUNDBERG, OF ALPENA, MICHIGAN, ASSIGNOR TO HURON INDUSTRIES, INC.,
OF ALPENA, MICHIGAN, A CORPORATION OF MICHIGAN.

GASKET FOR ROTATING KILNS.

Application filed May 29, 1922. Serial No. 564,355.

To all whom it may concern:

Be it known that I, JOHN L. LUNDBERG, a subject of the King of Sweden, residing at Alpena, in the county of Alpena and State of Michigan, have invented certain new and useful Improvements in Gaskets for Rotating Kilns, of which the following is a specification.

This invention relates to kilns especially cement kilns. It has for its object a gasket maintained by gravity at the joint between the rotating kiln and the furnace wall, or between the kiln and any other stationary body with which either end is connected.

It is found desirable in the use of a cement kiln to conduct the products of combustion into a furnace chamber in which are located a plurality of water tubes for generating steam. This utilizes the heat which would otherwise be wasted, for useful purposes in transforming the heat energy into steam which can be made to do useful work about the plant. In order to couple up the cement kiln with a furnace of this kind it is necessary to have a fairly tight joint between the kiln and the furnace, otherwise cold air will be drawn in at this point and will affect the heat on the tubes. It has already been proposed to place a gasket at the joint and hold it in sealing relation with springs, but this has not proved very satisfactory in practice.

It is the object of the present invention to use a gasket and hold it in place against the rotating kiln by gravity. This gasket is carried on a carriage which runs on an inclined track that may have a universal adjustment within given limits to bring the gasket into a proper relation with the ring along which it slides and with the kiln body. This will be more fully explained hereafter.

In the drawings:—

Fig. 1 is a section taken on the line 1—1 of Fig. 2.

Fig. 2 is an elevation of the end of the kiln, the mouth of the furnace and the joint between them.

Fig. 3 is a cross section through the same parts.

In cement making the material to be roasted is introduced at the higher end of the rotating kiln body and discharged at the

lower end. Heat is generated at the lower end of the kiln by the combustion of powdered coal or some other fuel delivered through a suitable nozzle. The products of combustion are drawn up through the kiln body and discharged from the upper end of the kiln body. It has been found useful to use these products of combustion to generate steam hence they are now introduced into a furnace chamber where they come in contact with pipes or other containers in which is the water. Now it is necessary to secure a fairly tight joint between the rotating kiln and the furnace in order to economically use this heat. It is the object of the present invention to secure such a joint.

a designates the kiln body which is rotated by suitable gearing not shown; it is a relatively long cylinder approximately 100 feet in length and usually about 8 feet in diameter. This kiln is made of a metal shell lined with fire brick. It has a reduced neck portion *b* which extends into the mouth *c* of the furnace. Bolted to the shoulder formed by the junction of the neck with the body of the kiln is a ring *d*. Secured to the mouth of the furnace is a mouth ring *e* which slopes from the inner end to the outer end downwardly. Mounted on this ring is a gasket *f* which has a central opening sloping downwardly from the inside to the outside in a similar way to the slope of the ring *e*. This ring *f* is a large heavy casting weighing a ton or more. It has a groove *x* for containing a sealing ring *y*.

The gasket *f* will not ordinarily bear on the sloping ring *e* but is provided at each side with the brackets *h*, the lower ends of which form carriages with longitudinally running V-grooves *i*. These carriages ride on the rollers *f'* which are formed of two coned frustums matched together at their bases. These rollers are held between the carriage and the inclined track *j* which also have a V-groove *k* in which the rollers are supported. This track is held in a support *m*. The bolts *n* are threaded through the support at the bottom and may be adjusted by loosening the lock nuts to raise the track and the carriage bodily or tilt the same to the angularity of the gasket. Similarly the end bolt *o* can be adjusted to change the longitudinal position of the track while the bolts *p* may be adjusted

to change the position of the track laterally. Now obviously by careful adjustment of this carriage the gasket can be brought into a substantially concentric relation with respect to 5 the furnace ring *e* so that there will be clearance all the way around the two rings and hence no load upon the soft sealing ring *y*. The great weight of the gasket will cause it at all times to bear firmly against the rubber ring *d* on the rotating kiln and seal the joint 10 at this point.

Preferably I use packing *z* between the contacting surfaces of the gasket and the rubber ring *d*. This insures an absolutely air-tight 15 joint at this point. It will also be desirable to make the gasket *f* in two sections bolted together as at *l* so that it may be assembled easily in place.

This gravity gasket will be found a great 20 improvement over gaskets that are maintained in sealing relation by springs. The kiln moves longitudinally in its operation and consequently when springs are used they are more or less compressed depending upon 25 how close the end of the kiln approaches the furnace. Of course the more they are compressed the greater is their pressure upon the contacting rings. The consequence is that at all times the pressure on the contact- 30 ing surfaces is not uniform, being first light and then very heavy, depending upon the position of the end of the kiln with respect to the furnace. This results in a rapid wearing of the contacting surfaces and almost in- 35 variably results in breaking some or all of the springs in time. With some of the springs broken the gasket leaks and becomes quite unfit for the purposes intended. It is hard to repair gaskets of this kind because 40 the owners of these kilns can not afford to stop the kilns as it is customary to run them continually—24 hours in a day.

With the gravity operating gasket that I have designed, the inclination of the track is 45 relatively small, consequently this gasket, weighing over a ton and a half, bears against the rub-ring with only a light pressure—about 200 pounds for the entire surface of the gasket. This results in an effective sealing 50 that does not result in undue wear or friction occasioning power losses.

What I claim is:

1. In a joint for a rotating cylinder, the combination of a stationary member provided with a mouth, a rotating cylinder body having one end adjacent the mouth of said member and a gravity pressed gasket arranged to seal the joint between the end of the cylinder and the mouth. 55

2. In a joint for a rotating kiln, the combination of a stationary member provided with a mouth having a ring thereon, a rotating kiln having one end adjacent the mouth of said member and a gasket supported about the mouth ring and sealing the 60

joint between the mouth and the rotating kiln body by pressure exerted through the agency of gravity.

3. In a joint, the combination of a stationary member provided with a mouth and a ring supported about the mouth and sloping downwardly from the inner end to the outer end, a relatively movable body having one of its ends adjacent to said ring and a gasket mounted around the said mouth ring and held in sealing contact with the end of the body by gravity. 70

4. In a joint for a rotating body, the combination of a stationary member provided with a mouth, a ring supported about the mouth and a gasket slideable by gravity along said ring, a rotating body positioned adjacent to said mouth ring, the said gasket being maintained against the end of the body in sealing relation by gravity. 80

5. In a joint for a rotating body, the combination of a stationary member provided with a mouth and a ring supported about the mouth, a rotating body with one end adjacent to said ring, a gasket slideable along the ring by gravity and against the end of the body in sealing relation, and carriage for supporting said gasket concentric with the said mouth ring. 90

6. In a joint for a rotating body, the combination of a stationary member provided with a mouth, a ring supported about the mouth, a rotating body having one end adjacent to the ring, a rub-ring secured to the end of the body and a gasket slideable along the mouth ring by gravity and held by gravity in sealing relation with said rub-ring. 95

7. In a joint, the combination of a stationary member provided with a mouth, a ring supported about the mouth, a relatively movable body having one end adjacent the mouth ring, a gasket slideable along the mouth ring and against the end of the body by gravity, a carriage for supporting the said gasket, and an inclined track upon which the carriage runs and which has a universal adjustability. 100

8. In a joint for a rotating body, the combination of a stationary member provided with a mouth, a ring supported about the mouth and sloping from the inner end to the outer end, a rotating body adjacent to the end of said mouth ring, a gasket slideable downwardly along said sloping mouth ring and a carriage upon which the said gasket rides, the said gasket being maintained in sealing relation with the end of the body. 110

9. In a joint, the combination of a stationary member provided with a mouth, a ring about the mouth, a relatively movable body with one end adjacent to said ring, a gasket supported to slide along the said mouth ring and against the end of the body in sealing relation, a carriage for supporting the said gasket, an inclined track upon which 120

the carriage is supported and anti-friction rollers between the track and the carriage.

10. In a joint, the combination of a stationary member provided with a mouth, a ring about the mouth, a relatively movable body having one end adjacent the mouth ring, a gasket supported to slide along the mouth ring and against the end of the body

through the action of gravity, a carriage upon which the gasket is carried, an inclined track upon which the carriage runs and means for adjusting the position of the track to bring the gasket in proper relation with the end of the body and the mouth ring.

In testimony whereof I affix my signature.
JOHN L. LUNDBERG.
